UNITED STATES PATENT OFFICE.

MAX KAPLAN AND DAVID TALNOFER, OF NEW YORK, N. Y.

COMPOUND DIES.

Application filed September 17, 1927. Serial No. 220,110.

This invention relates to press tools and more particularly to hand operated compound dies used in the formation of circular sheet metal structures in which a plate or 5 like article is enframed or a double walled saucer shaped object formed.

The object of the invention is to provide a novel and practical arrangement of dies for producing the several operations on the 10 metal parts in sequence, all the several operations being performed in a single press and without change of its operative parts.

Although the device is shown as engaged with a hand actuated bench press, it will be 15 understood that the same is shown as illustrative only, and that any type of single acting press may be utilized for performing similar functions.

A preferred embodiment of the invention 20 is hereinafter described and shown in the accompanying drawings, forming a necessary part of this disclosure, and in which:—

Figure 1 is a top plan view of a conventional type of a hand operative bench press 25 as arranged for the final or infolding operation.

Figure 2 is a front elevational view of the same.

Figure 3 is a view similar to Figure 1 but 30 showing one of the dies outturned, as during the first operation.

Figure 4 is a front elevational view of the device shown in Figure 3.

Figure 5 is a side elevational view of the 35 press and parts in position for final operation.

Figure 6 is a fragmentary sectional view, showing the operative parts in position to accomplish the first operation.

40 Figure 7 is a similar view of the same but in position to perform the second and final operation.

Figure 8 is a fragmentary sectional view showing an article to be formed, as shaped 45 during the first operation.

Figure 9 is a similar view of the same completed.

Referring more in detail to the drawings, the numeral 15 is used to generally designate 50 the base of a conventional type of hand-lever operable press, the same being provided with openings, whereby it may be bolted to a bench or other suitable foundation.

Rising from the rear of the base is a 55 column 16, preferably of T-shaped cross section, the upper portion of the same being

curved toward the front and provided with an elongated vertical guide sleeve head 17, generally of circular cross section, and having at its central portion opposed extending horizontal hubs 18 bored to receive a spindle 19, one end being enlarged and fitted with a lever 20 provided with a handle at its end.

Midway between the hubs 18, a spur gear 21 is formed on the spindle, the same engaging with the rack teeth of a plunger 22 operably mounted in the press head 17, these parts being common and of well known construction.

Fixed on the levelled central upper side 70 of the press base 15 is a disc-like base 23 from which rises a circular block 24 having a convexly curved top 25 finished to suit the inner surface of the work part and act as the lower die during the first operation 75 in assembling the object.

Movably engaged on the peripheral surface of the die block 24 is a ring 26 having an expanded upper portion 27, the same presenting a distinct shoulder seat 26' to rest 80 upon the upper coil of a helical compression spring 28, in turn seated upon the die block base 23.

In the upper end of the ring enlargement 27 is an inner annular recess 27' circumjacent the die block 24, the recess having a bevelled outer wall and being suited to receive and act as a seat for a corresponding annular projection 29 extending from the under side of a die plate 30.

The plate 30 has a circular opening 30', its diameter being in excess of the die block 24 to an amount equal to the combined thickness of the parts to be formed, and integral with the die plate, on its upper side, 95 is an annulus 31.

An upper die 32 is slidable in the die plate opening 30' to an amount controlled by a screw 33 in the annulus 31, acting as a key and engaging a slot in the upper die 32, as 100 can be seen in Figures 6 and 7, preventing relative rotation but permitting limited lineal movement.

A flange 34, equivalent in diameter to the annulus 31, has on its upper side a reduced collar 37 provided with a set screw to engage the plunger 22, which is tightly fitted in an axial opening 36 in the upper die, causing it to move as a unit with the plunger, and the lower surface 35 is concavely curved to suit the corresponding upper face 25 of the bottom die.

Extending laterally from the plate die 30 are lugs 38 and 39, respectively right and left hand, the former being bored to freely receive a spindle 40 capable of limited longitudinal movement and rotatable therein, the spindle having a collar 41 equal in length to the height of the annulus 31.

Rigidly fixed on the collar 41 is a spacing block 42 having a curved edge 42' shaped at a radius equal to the diameter of the upper die 32 and capable of being swung thereagainst when the block is interposed between the top of the annulus 31 and under side of the flange 34.

15 Rigidly fixed to the lower end of the spindle 40 is a circular plate 44 carrying on its lower side an intermediate die holder 45 capable of being swung into axial registration with the dies 24 and 32, the plate 44 having a stop pin 46 to engage in the bottom of a recess 47 in the die plate lug 39.

20 In the top of the die holder 45 is an annular recess 48 corresponding in all respects to the recess 27 and like it being capable of receiving the annular projection 29, when the die holder 45 is moved into operative position; it is to be noted that the inner edge 48' of this recess is bevelled, as best seen 25 in Figure 7.

25 Extending downward from the die holder 45 is an annular projection 49, the same being an exact counterpart of the projection 29 and like it suited to enter and rest upon the seat 27' of the ring 26.

30 Fitted to move in the opening 43 of the die holder is a circular die 50 having a flat level upper face 51 and a concave lower face 52 corresponding to the die block face 25 on which it is seated when in operative position, as best seen in Figure 7.

35 An air passage 53 of small diameter passes through the die 50 and in its edge is a key slot 54 to receive the point of a screw 55 reaching through the wall of the holder.

40 In Figures 8 and 9 enlarged partial views of the work comprising a small conventional pocket mirror are shown, the same consisting, for illustration only, of a circular metal plate "a" previously given a concave shape 45 and provided with a depending flange "b".

45 The outer transparent cover "c" of celluloid overlies a paper sheet "d", such as a photographic print, and all are to be crimped to firmly hold a flange "e" formed on a frame ring "f" which supports an object, such as a mirror "g".

50 In operation the upper die 32 and plate 30 are raised by the handle 20 and the intermediate die 50 with its holder 45 turned outwardly, causing the distance block 42 to enter below the flange 34 and contact with the die 32, the plate 30 being moved by gravity to its lowermost position.

55 Thereupon the metal plate "a" is placed

on the surface of the recess 27, the ring 26 being raised by the spring 28 above the top of the bottom die 24, and the paper and celluloid discs disposed over the metal, their edge being guided by the bevelled wall of the recess, care being taken to centralize the plate "a" so it will register with the face 25 of the bottom die.

Upon actuation of the handle 20 the upper die 32 is forced downwardly, together with the plate die 30, through the intermediary of the block 42, curling the parts "c" and "d" at their edges about the flange "b" of part "a".

60 On moving the lever 20 in the opposite direction, the die 32 is raised and also the plate die 30, bringing up the plate and crimped discs "a", "c" and "d", the same adhering within the plate die opening 30'.

65 Without removing these parts the mirror "g", in its frame "e"—"f", is laid on the level surface of the intermediary die 50 to extend thereabove and the same swung on the axis of the pivot 40, over the bottom die 24, until the stop pin 46 has reached its limit in the recess 47, this movement obviously clearing the block 42 from under the flange 34.

70 Upon actuating the lever 20 to force the die 32 downwardly the crimped flanges of the paper and celluloid discs are entered over the frame flange "e" and the bevelled wall 48' of the recess 48 produces a further in-reaching crimping effect of the parts "b", "c" and "d", causing them to engage the frame flange "e" and form the article shown 75 in Figure 9.

75 The article thus formed rests on the surface of the intermediate die 50 which, after the upper dies have been raised, may be swung outwardly and the finished article 80 removed ready for use.

85 From the foregoing it will be apparent that a novel and practical compound die has been disclosed easily capable of producing a wide range of articles similar in nature to that illustrated and composed of a plurality of parts whereby ornamental and useful objects are readily made.

90 It is to be understood that various changes and modifications may be resorted to, such as are well within the ability of a mechanic to produce, without departing from the general scope of the appended claims.

95 Having thus described our invention, what we claim as new and desire to secure by Letters Patent, is:—

1. In a hand press, a fixed lower die, a work receiving ring normally spring raised above said die, an upper die fixed on the plunger of said press, a plate die slidably mounted on the upper die and having lateral extensions, an intermediate die having a pivot rotatable in one of said extensions, said intermediate die being movable into position between the upper and lower dies, and a 100

block carried by said pivot engageable between said upper die and said plate die.

2. In a hand press, a fixed lower die, a work receiving ring normally spring raised above said die, an upper die fixed on the press plunger, a plate die limitedly slideable circumjacent the upper die and having a part to engage said ring, a lateral lug on said plate die having a pivot movably mounted therein, a die holder carried by said pivot, said die holder being registerable with said plate die and ring, and a die carried by said holder to register with said upper and lower dies when in one position and to be swung 15 beyond their confines when in another position.

3. In a hand press, a fixed lower die, a work receiving ring normally spring raised above said die, an upper die fixed on the press plunger, a plate die limitedly slideable circumjacent the upper die and having a part to engage said ring, opposed lugs on the sides of said plate die, one of said lugs having a pivot rotatably mounted therein, a die holder 25 carried by said pivot, an intermediate die floatingly supported by said holder and capable of registration with said upper die, and a distance block carried by the upper end of said pivot to enter between a portion 30 of said upper die and said plate die when the intermediate die is turned outwardly on its pivot.

4. The combination in a hand press having an upper and a lower die, of a work receiving ring on said lower die, said ring being normally spring raised, a plate die slideable on the upper die, a flange on said upper die to exert pressure on said plate die when performing one operation, and a block mov-

able into intercepting position between the 40 flange and plate die when performing another operation, said plate die having a part to engage said ring when the block is in operative position.

5. The combination in a hand press having 45 an upper and a lower die, of a flange on said upper die, a plate die keyed to slide on the upper die, an intermediate die pivoted to swing below said upper die, a block actuated by the intermediate die when in an inoperative position to interpose said flange and plate die and when in operative position to permit direct contact therebetween.

6. The combination with a press having 55 upper and lower dies carried respectively by the plunger and base of the press, of a pair of outer dies slideable respectively on the upper and lower dies, means for normally raising the lower outer die, inner and outer dies pivoted to said outer upper die during 60 one operation, and a block actuated by said swinging die to interpose between the inner and outer upper dies during another operation.

7. The combination with a press having 65 compound upper and lower dies, a block pivoted in the outer element of the upper die to maintain the inner and outer elements in adjustment for one operation, and a compound auxiliary die associated with said 70 block to enter between the compound upper and lower dies during the second operation.

Signed at New York, in the city of New York and State of New York, this 13th day of September, 1927.
